SHORT CIRCUITER FOR REPULSION
INDUCTION MOTORS

Alwin Borchers, Dayton, Ohio, assignor to The
Brown-Brockmeyer Company, Dayton, Ohio, a
corporation of Ohio

Application May 14, 1930. Serial No. 452,164

34 Claims. (Cl. 172—279)

My invention relates to short circuiters for repulsion induction motors.

It is my object to provide a short circuiter for a repulsion induction motor in which the short circuiting means will have both an abutting and a wiping contact, will be controlled by a single spring and will snap into and out of engagement in order to provide snap contact.

It is a special object of my invention to eliminate garter springs, to eliminate contact weights and to eliminate rocking and tilting contact-making segments.

It is my object to provide a short circuiter which will move bodily and rotatably about the shaft on which it is mounted to give a wiping contact.

It is a further object to provide several centrifugal weights so arranged as to move a contact member disk uniformly to and from the commutator segments and which will maintain such disk always in a plane at right angles to the armature shaft without tilting or binding so that all of the commutator segments will be simultaneously shortcircuited.

It is a further object to provide for perfect freedom of movement rotatably of the entire short circuiter on the shaft for the purpose of bringing the contact fingers into engagement with different commutator segments at each contact-making operation.

It is a further object to provide a novel form of snap mechanism which will control the weights but which will not be directly a part of the short circuiter members. It is my object to provide a few very heavy weights instead of a plurality of lighter contact-making segments.

It is my object to provide a ball bearing engagement between the weights and the guides for the weights and the snap action restraining means for the weights so as to provide a uniform rate of movement and resistance to each of the weights to thereby get a delicate but very accurate control that can be positively operated.

It is my object to have a single, strong and easily manufactured spring eliminating the delicate and uncertain actions of garter springs heretofore used, which are directly swung upon weights and make contact with the commutator bars.

It is my object to employ as contact making means conducting members in themselves inherently resilient and therefore self accommodating to irregularities in the commutator faces and being independently thus adjustable will not disturb the companion contact making means

engaging other commutator segments, which has been a disadvantage of weights themselves making contact with the commutator bars because the maladjustment or overmovement of one interferes with the remainder during the contact-making operation.

Referring to the drawings:

Figure 1 is a perspective of the motor with the short circuiter in position;

Figure 2 is a top plan view of the complete 65 circuiter;

Figure 3 is a section through the shaft showing the circuiter in elevation partially broken away;

Figure 4 is an inside view of the segment guide;

Figure 5 is a section on the line 5—5 of Figure 4;

Figure 6 is a vertical section taken transversely of the weight;

Figure 7 is a vertical section taken longitudinally of the weight;

Figure 8 is a top plan view of the weight;

Figure 9 is a bottom plan view of the weight;

Figure 10 is a section through the one-half of the circuit maker and breaker and a portion of the armature with the armature shaft in full 80 lines showing the parts in at-rest position;

Figure 11 is a similar view with the parts in restraining position just before snapping into contact position;

Figure 12 is a similar view showing the contact 35 position.

Referring to the drawings in detail, 1 is an armature shaft having an armature generally designated 2 with insulations 3 supporting the commutator bars 4. These bars have contact-making faces 5.

Mounted upon the shaft 1 is a split ring 6 mounted in the grooves 7 of the shaft 1 serving as an abutment for the ring 8 which is loosely mounted upon the shaft 1. This loose mounting 95 is shown somewhat exaggerated for the purpose of illustration, but it is normally sufficient to permit free turning of the ring 8 and its associated parts upon the shaft 1. This ring has mounted upon it permanently the weight guide 100 generally designated 9. This guide is provided with three pairs of slots 10 between which depends a guiding surface 11 having a shoulder 12 thereon. The slots 10 communicate with the central opening 13 in the guide which has a conical disk. They do not extend through the periphery of the disk.

Each guiding tongue 11 acts as a support for the reciprocating weights, of which there are three. These weights are designated 14 and are 110

provided with an upstanding portion 14a and a horizontal portion 14b so that they are L-shaped in section. A diagonal slot 15 extends from the lower corner 16 of the weight into and through the angle at 17 made by the upright arm 14a and the horizontal arm 14b. Substantially diagonally disposed and in a plane at substantially right angles to the slot 15 is an aperture 18 known as a ball carrier in which are mounted two balls 19 and 20. The outer ball serves to engage the rib 12 on the tongue 11 to resist the inward and outward movement of the weight and to give snap action to the short circuiter. These weights are entirely free and independent of one another. They are not connected to any springs and they are free to move under the influence of centrifugal force as they are guided in a diagonal and radial path by the tongue 11.

The upright member 14a of the weight has an upper vertical face 21. The horizontal arm of the weight is provided with an upright vertical face 22. The face 21 engages the periphery of a rigid ring 23 which is provided with a right angle offset portion 24 and a depending inner portion 25 that is engaged by the face 22 of the weight. Thus the weight bears against the ring 23 near its top and near its bottom and as the weights are distributed equidistant about the shaft 1, the ring 23 is moved inwardly and outwardly always in a plane at right angles to the major axis of the armature shaft 1. The movement of this ring under the influence of the weights is controlled and resisted by the axial spring 26, one end of which engages the lower edge of the plate 23 and the other end of which engages the armature 2.

Mounted upon the angular portion 24 of the ring 23 is a ring of insulating material, such as bakelite, designated 27, that is U-shaped in cross section. Within this U-shaped ring is carried a thin collar of strong copper designated 28 which is slotted at 29 into a plurality of independent resilient fingers 30 which make contact with the commutator bars 4 upon the faces 5. It will be observed that any irregularities in these faces will be accommodated by the fingers 30 independently one of the other.

It will be further understood that the three very heavy independent weights have no contact making function. It will be further observed that there is no restraining spring, such as a garter spring, employed but only an axial spring.

It will be understood that I desire to comprehend within my invention such modifications as may be necessary to adapt it to varying conditions and uses.

Having thus fully described my invention, what I claim as new and desire to secure by Letters Patent, is:—

1. In a short circuiter, a commutator, short circuiting means, yielding means normally maintaining the short circuiting means in an inoperative position, weights adapted to move the short circuiting means into short circuiting position, and diagonally disposed stationary guide means therefor adapted to slidably guide the weights, said guide means consisting of a slotted disc.

2. In a short circuiter, a shaft, a commutator, yielding means slidable longitudinally of the shaft for short circuiting said commutator, a spring resisting the bodily movement of said yielding means to and from the commutator, weights having diagonally disposed slots adapted to overcome said spring and move said short circuiting means into short circuiting engagement with the

commutator, and diagonally-disposed guiding means in said slots for guiding said weights.

3. In a short circuiter, a shaft, commutator bars having ends exposed, short circuiting means adapted to engage said ends, and independent slidable weights for moving said short circuiter means, each weight having a slot therein, means in each slot to guide said weights, and means to yieldingly resist the bodily movement of the weights and the short circuiting means together. 85

4. In a short circuiter, a shaft, commutator bars, a short circuiting ring having a plurality of relatively yieldable fingers, a supporting ring therefor insulated therefrom, yielding means for maintaining said ring in inoperative position, weights adapted to engage said ring, and means for guiding said weights. 90

5. In a short circuiter, a shaft, commutator bars, a short circuiting ring having a plurality of relatively yieldable fingers, a supporting ring 95 therefor insulated therefrom, yielding means for maintaining said ring in inoperative position, weights adapted to engage said ring, and means for guiding said weights diagonally.

6. In a short circuiter, a shaft, commutator bars, a short circuiting ring having a plurality of relatively yieldable fingers, a supporting ring 100 therefor insulated therefrom, yielding means for maintaining said ring in inoperative position, weights adapted to engage said ring, and means 105 for guiding said weights diagonally with the faces of said weights in slidable engagement with said ring.

7. In a short circuiter, a shaft, a commutator having commutator bars, a diagonally-disposed 110 guiding means, weights independently mounted thereon adapted to move transversely thereof and longitudinally thereof, a shoulder on said guide, means on said weights engaging said shoulder and adapted to ride thereover, a contact making 115 means operated by said weights, a supporting ring for said contact making means, and a yielding means engaging said commutator and said ring.

8. In a short circuiter, a shaft, a commutator having bars, a plurality of diagonally-disposed 120 guides, weights threaded thereon for slidable and transverse movement on said guides, a ring engaged by said weights, a spring resisting the movement of the ring, and a ring of contact making fingers insulated from but mounted upon said 125 ring first mentioned.

9. In a short circuiter, a shaft, a commutator having bars, a plurality of diagonally-disposed guides, weights threaded thereon for slidable and transverse movement on said guides, a ring engaged by said weights, a spring resisting the movement of the ring, and a ring of contact making fingers insulated from but mounted upon said 130 ring first mentioned, and means for loosely mounting said guides and said first mentioned 135 ring on the shaft.

10. In a short circuiter, a shaft, a commutator having bars, a conical disk mounted on said shaft having a plurality of spaced tongues communicating with a central aperture, weights threaded 140 on each of said tongues, a shoulder on each tongue, and a ball bearing on each weight adapted to engage with and ride over said shoulder, and a contact-making means controlled by said weights. 145

11. In a short circuiter, a shaft, a commutator having bars, a conical disk mounted on said shaft having a plurality of spaced tongues communicating with a central aperture, weights threaded on each of said tongues, a shoulder on each tongue, 150

- and a ball bearing on each weight adapted to engage with and ride over said shoulder, a contact-making means controlled by said weights, a ring engaged by said weights carrying said contact making means, and a spring resisting the movement longitudinally of the shaft, ring, weights and contact-making means.
12. In a short circuiter, a conical guide having a plurality of fingers extending inwardly, a shaft mounted centrally of said guide, L-shaped weights loosely mounted on said fingers, ridges on said fingers, balls carried by said weights, a ring engaged by said weights, a spring engaged by said ring, and contact-making means carried by said ring.
13. In a short circuiter, a conical guide having a plurality of fingers extending inwardly, a shaft mounted centrally of said guide, L-shaped weights loosely mounted on said fingers, ridges on said fingers, balls carried by said weights, a ring engaged by said weights, a spring engaged by said ring, and contact-making means carried by said ring, said weights having spaced faces for engaging said ring at different distances from its center whereby it is maintained in a plane at right angles to the axis of the shaft.
14. A new article of manufacture for use as short circuiter weights comprising a right angle body having a diagonal slot therein extending from the outside corner to the inside angle thereof and having a ball receiving socket communicating with said slot, and a pair of balls mounted therein, one of which partially projects from the socket into the slot.
15. A new article of manufacture for use as short circuiter weights comprising a right angle body having a diagonal slot therein extending from the outside corner to the inside angle thereof and having a ball receiving socket communicating with said slot, a pair of balls mounted therein, one of which partially projects from the socket into the slot, and a cam guiding face forming the upper wall of said slot extending out of the slot along one wall of the weight.
16. A new article of manufacture for use as short circuiter weights comprising a right angle body having a diagonal slot therein extending from the outside corner to the inside angle thereof and having a ball receiving socket communicating with said slot, a pair of balls mounted therein, one of which partially projects from the socket into the slot, a cam guiding face forming the upper wall of said slot extending out of the slot along one wall of the weight, and ring engaging faces arranged vertically but displaced from one another on each arm of said L-shaped weight.
17. In a short circuiter, the combination of a conical plate having a central eye and a plurality of spaced fingers communicating therewith, ribs on said fingers, L-shaped weights threaded on said fingers and balls carried in said weights rolling one on the other, one of said balls engaging with the shoulder on the fingers.
18. In a short circuiter, the combination of a conical ring having a central aperture and a plurality of separated fingers having their free ends forming the margin of said aperture, L-shaped weights having diagonal slots through their corners for loose mounting upon said fingers, a pair of balls mounted in sockets in said weights communicating with said slots, the outer of said balls extending into the slot and engaging the shoulder on its finger thereby resisting the movement of the weight and displacing it laterally as it is guided diagonally on the fingers.
19. In a short circuiter, the combination of a conical ring having a central aperture and a plurality of separated fingers having their free ends forming the margin of said aperture, L-shaped weights having diagonal slots through their corners for loose mounting upon said fingers, a pair of balls mounted in sockets in said weights communicating with said slots, the outer of said balls extending into the slot and engaging the shoulder on its finger thereby resisting the movement of the weight and displacing it laterally as it is guided diagonally on the fingers, said weights having arms with vertically-disposed offset faces.
20. In a short circuiter, the combination of a conical ring having a central aperture and a plurality of separated fingers having their free ends forming the margin of said aperture, L-shaped weights having diagonal slots through their corners for loose mounting upon said fingers, a pair of balls mounted in sockets in said weights communicating with said slots, the outer of said balls extending into the slot and engaging the shoulder on its finger thereby resisting the movement of the weight and displacing it laterally as it is guided diagonally on the fingers, said weights having arms with vertically-disposed offset faces, a ring having an angular offset engaging said faces, a spring resisting the movement of said ring, a collar having a plurality of yielding fingers insulated from but mounted upon said ring, a commutator with bars engaging said spring, and a shaft for supporting the foregoing mechanism, and means on said shaft for positioning said guide thereon.
21. In a short circuiter, a shaft, a commutator having bars, a ring, insulated yielding fingers carried thereby, a spring resisting the movement of the ring, L-shaped weights engaging the ring, diagonal guides for the weights, and means to impart a snap action to the weights in either direction as they are diagonally guided inwardly and outwardly.
22. In a short circuiter, a commutator, short circuiting means, yielding means normally maintaining the short circuiting means in an inoperative position, a cone shaped stationary guide means, weights slidable on said guide means adapted to move the short circuiting means into short circuiting position, and means on the stationary guide means to temporarily resist the movement of the weights in order to provide a snap action for sudden engagement and disengagement of the short circuiting means, said weights contacting said short circuiting means adjacent the upper and lower extremities of said short circuiting means.
23. In a short circuiter, a commutator, short circuiting means, yielding means normally maintaining the short circuiting means in an inoperative position, a cone shaped stationary guide means, weights slidable on said guide means, adapted to move the short circuiting means into short circuiting position, and means on the stationary guide means to temporarily resist the movement of the weights in order to provide a snap action for sudden engagement and disengagement of the short circuiting means, said last named means comprising a barrier and rotatable means engaging said barrier and adapted to ride thereover depending upon the centrifugal force applied, said weights contacting said short circuiting means.

cuiting means adjacent the upper and lower extremities of said short circuiting means.

24. In a short circuiter, a shaft, a commutator, a diagonal stationary guide, weights movable on said guide, a separate short circuiting means moved by said weights, yielding means for resisting the movement of the short circuiting means, and cooperating snap means on the guide and the weights, said weights contacting said short circuiting means adjacent the upper and lower extremities of said short circuiting means.

25. In a short circuiter, a shaft, a commutator, a cone shaped stationary diagonal guide, weights slidable on said guide, a separate short circuiting means moved on said weights, yielding means for resisting the movement of the short circuiting means, and means on the guide to resist temporarily the movement of the weights to and from the shaft in order to provide a snap action of the short circuiting means, said weights contacting said short circuiting means adjacent the upper and lower extremities of said short circuiting means.

26. In a short circuiter, a shaft, a commutator, a cone shaped guide means, weights on said guide, a separate short circuiting means moved by said weights, yielding means for resisting the movement of the short circuiting means, and means on the guide means to resist temporarily the movement of the weights to and from the shaft in order to provide a snap action of the short circuiting means, said guide means being arranged for the weights for diagonal and radial movement to and from the commutator, said weights contacting said short circuiting means adjacent the upper and lower extremities of said short circuiting means.

27. In a short circuiter, a shaft, a commutator, a guide having shoulders thereon, weights on said guide, a separate short circuiting means moved by said weights, yielding means for resisting the movement of the short circuiting means, ball means on the weights to engage the guide to resist temporarily the movement of the weights to and from the shaft by engaging the shoulders in order to provide a snap action of the short circuiting means, said guiding means being arranged for the weights for diagonal and radial movement to and from the commutator, and means for permitting transverse movement of said guide at intervals, said weights contacting said short circuiting means adjacent the upper and lower extremities of said short circuiting means.

28. In a short circuiter, a shaft, a commutator, yielding means sliding longitudinally of the shaft for short circuiting said commutator, a spring resisting the bodily movement of said yielding means to and from the commutator, a guide having shoulders thereon, weights on said guide adapted to overcome said spring and move said short circuiting means into short circuiting engagement with the commutator, and ball snap means on said weights to engage the shoulders, said weights contacting said short circuiting means adjacent the upper and lower extremities of said short circuiting means.

29. In a short circuiter, a shaft, commutator bars having ends exposed, short circuiting means adapted to engage said ends, a stationary guide having shoulders, independent slidable weights for moving said short circuiter means, means to

guide said weights, and means to yieldingly resist the bodily movement of the weights and the short circuiting means together, and ball means on the weights to engage the shoulders and temporarily resist the movement of said weights and short circuiter means during a period of their motion in either direction, said weights slidably contacting the surface of said short circuiting means at separated areas only. 80

30. In a short circuiter, a shaft, a commutator having commutator bars, a diagonally disposed cone shaped guiding means, weights independently mounted thereon adapted to move transversely thereof and longitudinally of the shaft, a shoulder on said guide, and means on said weights engaging said shoulder and adapted to ride thereover, and a contact making means operated by said weights, said weights contacting said short circuiting means adjacent the upper and lower extremities of said short circuiting means. 85

31. In a short circuiter, a shaft, a commutator having bars, a cone shaped guide from the shaft towards the commutator bars, a plurality of weights on said guide, a ring between the weights and the commutator engaged by said weights, means on the weights engaging the guide to resist the movement of said weights and to suddenly release the weights, a ring of contact-making fingers insulated from but mounted upon said ring, said weights contacting said ring adjacent the upper and lower extremities of said ring. 90

32. In a short circuiter, a shaft, a commutator having bars, a cone shaped guide from the shaft towards the commutator bars, a plurality of weights on said guide, a ring between the weights and the commutator engaged by said weights, means on the weights engaging the guide to resist the movement of said weights and to suddenly release the weights, a ring of contact-making fingers insulated from but mounted upon said ring, 100 means for restraining the upward movement of said guide but permitting the free rotatable movement of said guide, weights and ring upon said shaft, said weights contacting said ring adjacent the upper and lower extremities of said ring. 105

33. In a short circuiter, a shaft, a commutator having bars, a cone-shaped guide from the shaft towards the commutator bars, a plurality of weights on said guide, a ring between the weights and the commutator engaged by said weights, means on the weights engaging the guide to resist the movement of said weights and to suddenly release the weights, whereby said weights may move diagonally of said shaft, and a ring of contact-making fingers insulated from but mounted upon said ring. 115

34. In a short circuiter, a shaft, a commutator having bars, a cone-shaped guide from the shaft towards the commutator bars, a plurality of 120 weights on said guide, a ring between the weights and the commutator engaged by said weights, means on the weights engaging the guide to resist the movement of said weights and to suddenly release the weights, whereby said weights may move diagonally of said shaft, a ring of contact-making fingers insulated from but mounted upon said ring, means for restraining the upward movement of said guide but permitting the free rotatable movement of said guide, weights and ring upon said shaft. 125
